BURNER, PARTICULARLY FOR GAS
TURBINESHerbert Kruppe, Decize, Nievre, France, assignor
to Hermann Oestrich, Decize, Nievre, France

Application March 7, 1950, Serial No. 148,175

Claims priority, application France
March 15, 1949

8 Claims. (Cl. 60—39.72)

1

In conventional burners, particularly those designed for gas turbines, the mixture formation and combustion take place in the turbulent zone caused by a resistant body, for instance a cone or a frustum of a cone, arranged in the stream of air for supporting combustion.

Such burners which are called conical burners, mainly comprise an outer sleeve and an inner one, in the shape of concentric frustums of a cone allowing passage of primary air therebetween for mixture further on with fuel injected through the centre.

It is quite obvious that the mixture formation is most intimate in the zone wherein direct contact occurs between air and fuel. It decreases in the outer layers of the stream which, owing to this fact, play a less active part in combustion. This causes a poor distribution of temperatures with a sharp peak on the axis of the burner.

It is an object of my invention to provide a burner which improves homogeneity of the mixture and ensures an even distribution of temperatures within a wider space. For this purpose, the inner sleeve along the outlet edge of which the mixture formation starts, is widened by radial corrugations, and if need be, the outer sleeve is similarly corrugated to have festoons projecting into the free space between the inner sleeve corrugations, in such a way that the passage for air for supporting combustion be reduced to a relatively narrow slot along the outlet edge of the corrugations. Instead of corrugations I may also provide appropriate shaped pieces arranged between the outer sleeve and the inner one. The efficient length of the outlet edge is thus considerably increased and hence the zone wherein mixture formation takes place is widened. Combustion is therefore effected in that widened turbulent zone whose cross-section depends upon the radial extent of the corrugations. The reduction in the annular space between the inner and outer sleeve does not cause a resistance to flow much greater than in the case of conventional conical burners provided the number of burners or the inlet cross-section for secondary air are correspondingly increased.

However, the improved homogeneity of the mixture thus obtained offers the advantage of ensuring a higher combustion efficiency which may reach 100%.

A further object of my invention is to provide a burner of the type just described which is so constructed that the temperature peak is shifted away from the burner axis. With that object in view, I may either draw the corrugations nearer

2

to each other in the portion of the burner which lies in the direction along which the temperature peak is to be displaced, or increase the cross-section of said corrugations relatively to the other ones. Thereby a greater amount of fuel and/or a smaller amount of primary air are swerved in this direction with a corresponding unsymmetrical temperature distribution.

With burners as described it is possible, even at the highest flow velocities, to provide ignition of the various burners according to a predetermined sequence in the case of arrangement in an annular combustion chamber. For this purpose, it is only necessary to arrange the burners in such a way that the hot gas jets from two successive burners meet.

Other objects and advantages of the invention will be apparent during the course of the following description. In the accompanying drawing forming a part of this application and in which like numerals are employed to designate like parts throughout the same,

Fig. 1 is a plan view of a burner embodying my invention, as seen in the direction opposite to the jet,

Fig. 2 is a section of the burner shown in Fig. 1 along line 2—2 of Fig. 1.

Fig. 2a is a section of the burner shown in Fig. 1 taken along the line 2a—2a of Fig. 1.

Fig. 3 is a plan view of another burner according to the invention, as seen in the direction opposite to the jet,

Fig. 4 is a sectional perspective view taken along line 4—4 of Fig. 3, and

Figs. 5 and 6 show embodiments of a burner of the type shown in Figs. 3 and 4, seen in the direction opposite to the jet, and having an unsymmetrical temperature distribution.

In Figs. 1, 2 and 2a, the inner sleeve 1 is secured, for instance by welding, to the outer sleeve 2 at the points of contact 3. The widening of the inner sleeve 1 and the corresponding re-entrant portions of the outer sleeve 2 are clearly seen. Between these two sleeves are passages 4 for air for supporting combustion, corresponding to the six festoons or corrugations 5 arranged in star formation (Fig. 1). The corrugations may also be distributed otherwise, by selecting an arrangement comprising for instance eight or nine corrugations.

In the embodiment of Figs. 3 and 4, the inner sleeve generally designated by numeral 1 comprises a rearwardly flaring, front portion 10 followed with a rearwardly tapering rear portion 11. Projecting from the front into inner sleeve

1 is a fuel injector 7, shown in dash and dot lines. Around inner sleeve 1, in coaxial relationship therewith, is a rearwardly flaring outer sleeve 2 radially spaced from the sleeve 1 to provide an intermediate annular passage 4 for air supply. Sleeve 2 is fast with a support 8 therefore for at its forward end as shown, and the rear end of the combustion chamber is shown at 9.

The forward portion 10 of inner sleeve 1 is formed with a forwardly flaring extension 13, said extension and the rear portion of outer sleeve 2 having corresponding indentations to accommodate channel members or inner sleeve extensions 6 which are frontwardly concave and provide radial baffles for the air flow supplied through passage 4, so as to divide the air effluent into a plurality of separate jets. The channel extensions 6 are sheet metal strips, longitudinally bent and secured, for instance by welding, to the outer sleeve 2 and extension 13 of inner sleeve 1 in the corresponding indentations thereof.

It will be appreciated that owing to the shape of a double cone assumed by inner sleeve 1, the injector 7 lies in a relatively quiescent, sheltered zone, and also that in view of the concave shape of channel extensions 6, eddies are produced in the channels, i. e., on the rear side thereof, promoting mixture of air with the fuel spray from the injector.

In Figs. 5 and 6, an unsymmetrical distribution of channel members and the provision of channel members 6 of different width or peripheral extent are respectively shown. In the former case, three channel members 6' have been moved nearer to each other (top of Fig. 5), while the other ones are evenly distributed over the remainder of the periphery. In Fig. 6, distribution is symmetrical; however it is noted that the three top channel members 6' have been widened.

In both cases, the result achieved is such that a greater proportion of fuel injected is directed towards the side thus altered of the burner and that the temperature peak is thereby displaced away from the axis of the burner, in the selected direction. This same result may take place owing to the smaller amount of air passing through the reduced slots, or else to both effects simultaneously.

It is to be understood that the forms of the invention herewith shown and described are to be taken as preferred examples of the same and that various changes in the shape, size and arrangement of parts may be resorted to without departing from the spirit of the invention or the scope of the subjoined claims.

What I claim is:

1. In a burner, particularly for a gas turbine plant, the combination of an outer sleeve which generally flares rearwardly, an inner sleeve supported within said outer sleeve, in coaxial relationship therewith but spaced radially therefrom to provide an intermediate annular passage for supply of air therethrough in a rearwardly direction, said inner sleeve comprising a rearwardly flaring, front portion providing a relatively quiescent, sheltered zone for receiving a rearwardly and axially directed stream of fuel and a rear portion having a plurality of separate concave, fuel guiding, channel extensions which diverge rearwardly and away from the sleeve axis in star formation to the rear periphery of said outer sleeve so as to provide a series of radial baffles across said annular space between said inner and outer sleeves for dividing the air effluent into a plurality of separate jets.

2. The combination of claim 1, wherein the distribution of said fuel guiding, channel extensions is unsymmetrical, said extensions being in closer proximity to one another over at least one sector of the rear periphery of said outer sleeve than over the remainder of said periphery.

3. The combination of claim 1, wherein the total peripheral extent of said fuel guiding, channel extensions over a sector of the rear periphery of said outer sleeve is greater than over the diametrically opposite sector.

4. In a burner, particularly for a gas turbine plant, the combination of an outer sleeve which generally flares rearwardly, said sleeve having relatively shallow corrugations provided in lengthwise direction, the depth of which increases in rearward direction; with an inner sleeve, also flaring rearwardly, formed with relatively deep corrugations which correspond with those of said outer sleeve and also have a depth increasing rearwardly, said inner sleeve being attached to the rear periphery of said outer sleeve solely in the portions of maximum diameter thereof, so as to be supported co-axially with said outer sleeve and to provide between said inner sleeve and said outer sleeve a generally annular air passage ending rearwardly in a ring series of V-shaped interspaces.

5. The combination of claim 4, wherein the corresponding corrugations in said sleeves are so designed and arranged that the various separate interspaces between said sleeves, providing the air passages, are generally convergent rearwardly.

6. In a burner, particularly for a gas turbine plant, the combination of an outer sleeve which generally flares rearwardly; an inner sleeve of less cross dimensions than said outer sleeve, located in the front portion of said outer sleeve in coaxial relationship therewith, to provide an inner, sheltered, relatively quiescent zone for receiving a rearwardly directed stream of fuel and an annular passage between said inner sleeve and said outer sleeve for supply of air therethrough in rearward direction; and a plurality of separate, rearwardly concave, channel members, radiating in star formation from and attached to the rear portion of the periphery of said inner sleeve and extending and attached to the rear portion of said outer sleeve, to provide baffles adapted to divide the air effluent from said annular passage into a plurality of separate jets.

7. The combination of claim 6, wherein said channel members are formed of bent sheet metal welded to said sleeves for bridging the same and supporting said inner sleeve from said outer sleeve.

8. The combination of claim 6, wherein said inner sleeve comprises a rearwardly flaring front portion followed with a rearwardly tapering intermediate portion from which said channel members radiate.
